CLAIM

The ornamental design for a toy rocking horse, as shown and described.

DESCRIPTION

FIG. 1 is a side elevational view of a toy rocking horse showing my new design, the side opposite being a mirror image;

FIG. 2 is an end elevational view thereof;

FIG. 3 is a top plan view thereof; and

FIG. 4 is a end elevational of the end opposite that shown in FIG. 2.

FIG. 1

FIG. 2

FIG. 3

FIG. 4
